UNITED STATES PATENT OFFICE.

JOHN KLINE, OF BELOIT, WISCONSIN.

DRAINER.

SPECIFICATION forming part of Letters Patent No. 678,404, dated July 16, 1901.

Application filed March 9, 1901. Serial No. 50,500. (No model.)

To all whom it may concern:

Be it known that I, JOHN KLINE, a citizen of the United States, residing at Beloit, in the county of Rock and State of Wisconsin, 5 have invented certain new and useful Improvements in Drainers, of which the following is a specification.

The object of this invention is to construct a drainer especially adapted for use in connection with bars on which the glasses are placed after being washed.

In the accompanying drawings, Figure 1 is an isometrical representation of my improved drainer. Fig. 2 is an isometrical representation of the rack. Fig. 3 is an isometrical representation of the rack-support. Fig. 4 is an isometrical representation of a drain-board, showing my improvements in connection therewith.

20 The rack-support comprises an inclined bottom 1, edges 2, an outwardly-extending flange 3, a depending lip 4, and corner portions 5, connecting with the lip and edges. The rack comprises the side angle-bars 6 and 25 the transverse bars 7, connecting the angle-bars. The side angle-bars of the rack rest on the outwardly-extending flange of the rack-support in a removable manner. The drainer is supported by the flange 3, resting

upon bars 8, in a manner to permit of its removal. 30

With the drainer in the position shown at Fig. 1 the rack will occupy a horizontal position, and the bottom being inclined will carry the drippings to the lowest end and discharge 35 them over the lip 4, which will direct them into a suitable receptacle.

At Fig. 4 is shown a drain-board with my improvements in connection therewith. The bars 8 are supported upon legs 9. A work-board 10 is supported by the bars. In this figure of the drawings are shown four of my improved drainers, and between each pair is located a basin 11, into which the water from two of the drainers drips. 45

I claim as my invention—

A drainer comprising a rack and a rack-support, the support having an inclined bottom, supporting-flanges and a downwardly-extending lip, and the rack having side angle-bars, and bars connecting the vertical portion of the angle-bars, the horizontal portions of the angle-bars adapted to rest upon the flanges of the rack-support. 50

JOHN KLINE.
